UNITED STATES PATENT OFFICE.

HENRY PETER CLAUSEN, OF MOUNT VERNON, NEW YORK, ASSIGNOR, BY MESNE ASSIGNMENTS, TO WESTERN ELECTRIC COMPANY, INCORPORATED, A CORPORATION OF NEW YORK.

TELEPHONE SYSTEM.

1,196,761.

Specification of Letters Patent. Patented Sept. 5, 1916.

Application filed May 11, 1915. Serial No. 27,349.

To all whom it may concern:

Be it known that I, HENRY PETER CLAUSEN, a citizen of the United States, residing at Mount Vernon, in the county of Westchester and State of New York, have invented certain new and useful Improvements in Telephone Systems, of which the following is a full, clear, concise, and exact description.

10 This invention relates to telephone systems, and particularly to systems in which means are provided for informing a calling subscriber when ringing current is applied to the line of the called subscriber.

15 Heretofore, various schemes have been devised for satisfying the calling party that his call is being sent as, for example, by transmitting a portion of the ringing current back over the calling subscriber's line, 20 but these schemes have proven unsatisfactory because very often the calling subscriber would mistake the induced ringing current upon his line for a busy tone and restore his receiver without giving the 25 called party an opportunity of answering. It is the object of this invention to provide a characteristic signal or tone not readily confused with other signals for notifying the calling subscriber when ringing current 30 is impressed upon the line of the called subscriber.

In accordance with this invention there is provided at a central office a source of ringing current adapted to be impressed 35 upon a subscriber's line. A signaling device is arranged to be actuated by said ringing current, and associated with said device is a telephonic element adapted to be inductively connected to the talking strands of an 40 operator's cord circuit.

This invention will be more clearly understood by reference to the accompanying drawing which shows a calling subscriber's station A and a called subscriber's station

45 B. Each of these substations are connected by means of line wires 1, 2 to a jack 3 at a central office. Associated with the line circuit is the customary line relay 4, line lamp 5 and cut-off relay 6. A connecting 50 cord circuit of a two-conductor type is shown having conductors 8 and 9 terminating respectively upon the tip and ring contacts of the answering and calling plugs 10 and 11 respectively. In each of these conductors a condenser 12 is inserted to inter-

rupt the conductive continuity of said conductors, and current from battery 13 is supplied to each half of said conductors through supervisory relays 14, 15 and 16, 17. In the answering half of the cord conductors the live pole of battery 13 is connected with the ring strand 9, through the winding of the ring supervisory relay 14, and the grounded pole of the battery connects with the tip strand 8 through the tip supervisory relay 15. In the calling plug portion of the cord the live pole of the battery has connection with the ring strand through the supervisory relay 16, and the grounded pole has connection with the plug tip strand through the supervisory relay 17. The supervisory relays 14, 15 conjointly control the supervisory lamp 18 of the answering end of the cord circuit, and likewise the supervisory relays 16 and 17 conjointly 75 control the supervisory lamp 19 of the calling line of the cord circuit. An operator's set is adapted to be bridged across the talking strands of the cord circuit by means of a listening key 20.

A source of ringing current 21 is adapted to be associated with the calling portion of the cord circuit by the actuation of a ringing key 22. A signaling device 23, such as a ringer, responsive to alternating current, is 85 arranged to be actuated by the ringing current from the source 21. Associated with the signaling device 23 is a telephonic element 24, connected in a manner conforming to standard practice with a transformer 25, 90 which is adapted to be connected to the ring side of the calling portion of the cord circuit through one of the contacts of the ringing key 22.

When subscribers A and B are connected 95 by inserting the answering and calling plugs 10 and 11 respectively into the line jack 3 of each subscriber's line, upon the operation of the ringing key 22, ringing current is applied to the line of the called subscriber B. Simultaneous with the application of this ringing current to the called subscriber's line the signaling device 23 is actuated. The actuation of this device produces a tone or ringing sound which is 100 transmitted back upon the line of the calling subscriber A, through the agency of the telephonic element 24 and the transformer 25. The circuit of this induced tone may be traced from battery, through the second- 105 110

ary winding of transformer 25, ring strand of conductor 12, out over the line and through the substation A, returning over the tip strand to ground, through the winding of supervisory relay 15. It will be noted that as this induced current is an alternating current, it will readily pass through the condenser 12. The calling subscriber hearing this tone will be given the impression that he actually hears the bell of the called party being rung. This signal is so characteristically distinctive that there is little likelihood that the calling subscriber will confuse it with the ordinary tone customarily transmitted back to a calling subscriber in event the line of the called party happened to be in use at the time the call is originated.

What is claimed is:

- 20 1. In a telephone system, a calling and a called subscriber's line terminating in line jacks at a central office, a link circuit for connecting said lines in conversation, a source of ringing current associated with said link circuit and adapted to be impressed upon the line of said called subscriber, means for giving an audible signal of characteristic tone, and means for converting said signal into current impulses corresponding characteristics impressed upon said calling subscriber's line when said ringing current is impressed upon said called subscriber's line.
- 25 2. In a telephone system, a calling and a called subscriber's line terminating in line jacks at a central office, a link circuit for connecting said lines in conversation, a source of ringing current associated with said link circuit and adapted to be impressed upon the line of said called sub-

scriber, a signaling device adapted to be operated by said ringing current, a telephonic element associated with said signaling device, and means for inductively connecting said telephonic element with the talking strands of said link circuit whereby the calling subscriber is given a characteristic tone whenever said ringing current is applied to said line.

3. In a telephone system, a calling and a called subscriber's line terminating in line jacks at a central office, a link circuit for connecting said lines in conversation, a source of ringing current associated with said link circuit and adapted to be impressed upon the line of said called subscriber, a ringer adapted to be operated by said ringing current, a telephonic element associated with said ringer, and means for inductively connecting said telephonic element with the talking strand of said link circuit whereby the calling subscriber is given the sound of a bell ringing when said ringing current is applied to said called line.

4. In a telephone system, subscribers' lines terminating at a central office, a link circuit having one end connected with one of said lines, a source of ringing current, means adapted to be actuated to impress current from said source upon the connected line, a source of tone signaling current, and a switch operated upon actuation of said means to connect said source of tone signaling current to the other end of said link circuit.

In witness whereof, I hereunto subscribe my name this 8th day of May A. D., 1915.

HENRY PETER CLAUSEN.
